PUNCHING APPARATUS

Robert Ruoff, Audubon, N. J.

Application August 20, 1954, Serial No. 451,101

8 Claims. (Cl. 164—50)

This invention relates to punching apparatus, and more particularly to a notching tool in the nature of a punch press for punching notches in sheet material along an edge thereof to provide a series of spaced tabs or the like which can be bent or otherwise deformed as desired.

There are numerous instances where it is desirable to provide spaced tabs along the edges of one or more members made from sheet materials, such tabs being useful for connecting these members to other members. For example, in sheet metal work, it is not uncommon to form out of sheet material a plurality of ducts or pipes which are to be connected to each other. Among the expedients employed for effecting the connections are tabs formed along the ends or edges of the ducts, the tabs on each duct being bent for reception within a next adjacent duct. Heretofore, it has been common practice to form these tabs by means of hand-manipulated shears. This is not only time consuming and expensive, but it also has the disadvantage of being relatively inconvenient to accomplish in the case of preformed ducts, tubes, casings and other similar devices commonly manufactured in the sheet metal art. Moreover, where it is desirable to space the tabs uniformly along the edge of the sheet material, a certain degree of skill is required on the part of an operator unless the work is previously marked or some suitable pattern is employed.

The primary object of my invention is to provide an improved notching tool for use in forming tabs or the like in sheet materials which is free from the aforementioned and other disadvantages inherent in hand-manipulated shear operations.

More particularly, it is an object of my invention to provide an improved notching tool which can be either hand operated or motor driven and which, in either case, is simple to operate.

Another object of my invention is to provide an improved notching tool which can readily accommodate either flat sheets or curved sheets, the latter in the form of tubes or pipes, for example.

Still another object of my invention is to provide an improved notching tool as aforesaid which is readily adjustable to receive work of different thicknesses.

A further object of my invention is to provide an improved notching tool as above set forth by means of which tabs or the like can be formed in the work at uniformly spaced intervals.

A still further object of my invention is to provide an improved notching tool as specified above which can be adjusted readily to provide varied spacing between tabs as desired.

Yet another object of my invention is to provide an improved notching tool for the purpose set forth which can be operated with great accuracy by even an unskilled worker.

It is also an object of my invention to provide an improved notching tool as aforesaid which is simple in construction, easy to operate, and highly efficient in use.

According to one form of my invention, the tool com-

prises a stand having a base on which a suitable die is mounted. The stand also carries a reciprocable ram to which a punch is secured for cooperation with the die. Either a hand crank or a suitable motor may be used

5 to operate the ram relative to the work to form a series of spaced notches along an edge thereof. The work, in the form of either a flat sheet or a pipe, is fed between the punch and die by a feed wheel which is operated in response to movement of the ram away from the 10 work. The degree of movement of the feed wheel during each cycle can be adjusted to provide suitable spacing between successive notches formed in the work by the punch, thereby controlling the size of the tabs provided between successive notches.

15 The novel features of my invention, both as to its organization and method of operation, as well as additional objects and advantages thereof, will be better understood from the following description, when read in connection with the accompanying drawing in which

20 Figure 1 is a front elevation of one form of notching tool according to my invention, the tool being shown partly broken away to clearly depict certain parts and being shown with a sheet of flat stock therein and with the feed wheel in engagement with the work,

25 Figure 2 is a side elevation of the tool, partly broken away, as seen from the right of Figure 1,

Figure 3 is a view similar to Figure 1 but showing a section of cylindrical pipe of sheet material mounted on the die and the adjacent work supporting wheel under the 30 feed wheel, and with the feed wheel raised from the work,

Figure 4 is an enlarged, fragmentary, perspective view showing one form of punch and die which may be used in my improved tool and the manner in which the punch and die cooperate with each other, and

35 Figure 5 is a fragmentary, plan view of a section of sheet material in which notches and tabs have been formed along one edge thereof by the tool of Figures 1 to 3.

Referring more particularly to the drawing in which 40 the same reference numerals designate corresponding parts throughout, there is shown a support comprising a stand 1 having a forwardly-extending base 3 and an upright portion 5 which has a forwardly extending block 7 above the base 3 and a bearing 9 at its upper end. The block 7 is provided with a vertical bore 11 and a vertical channel 13 for purposes to be set forth presently.

Secured to the base 3 by screws 15 is a die 17 formed with a suitable hole 19 having the shape of the notches 50 to be formed in the work. The die preferably has a convex, upper surface for a reason which will become apparent as the description proceeds. Arranged to cooperate with the die 17 is a punch 21 having a shank 23 which is received in an axial bore 24 in the lower

55 end of a reciprocable ram 25, the punch being locked to the ram by a set screw 27. The ram is slidably mounted in the bore 11 and is connected by a link 29 to an eccentric pin 31 on one end of a crankshaft 33 in the bearing 9. The crankshaft 33 may be rotated manually by means

60 of a crank 35 secured thereto or from a suitable motor (not shown), as may be desired. In any case, as the crankshaft rotates, it actuates the link 29 to effect reciprocal movement of the ram. Thus, the punch 21 is alternately brought into and out of engagement with a

65 piece of work 37 and into and out of cooperative relation with the die 17 to form notches 39 in the work and thus provide a series of tabs 40 along the edge of the work.

The work 37 may be either in the form of a flat sheet 70 of metal, rubber, leather, cardboard, plastic, cloth, etc., as shown in Figs. 1 and 2, or it may be curved or tubular in form, as shown in Fig. 3. In the latter case, the

tube or pipe 37a rests on the upper surface of the die 17. It is to provide a solid support of substantial area for the pipe that the upper surface of the die 17 is made convex as described previously. For supporting flat work, there is provided a platform or shelf 41 which is secured to a guide bar 43 by screws 45. The guide bar 43 rests on the base 3, being held thereon by screws 47, and serves to guide the work 37 or 37a as it moves past the punching station under the punch 21. A stripper 49 secured to the guide bar 43 by a screw 51 is engaged by the work 37 and keeps the work from being pulled up by the punch 21 when the latter moves upwardly after a punching operation. The parts punched out of the work 37 are deposited in a suitable receptacle (not shown) through a bore 53 in the base 3 aligned with the die hole 19.

For feeding the work past the punching station, there are provided a work supporting wheel 55, which is rotatably mounted on the base 3 by means of a stud 57, and a cooperating, peripherally serrated feed wheel 59. The feed wheel is rotatably mounted by means of a stud 61 on a bracket 63 which is slidably mounted in the channel 13 of the block 7. A stud 65 which passes through a vertical slot 67 in the bracket 63 and is threaded into the block 7 holds the bracket 63 on the block and limits sliding movement of the bracket on the block.

Secured to the upper end of the block 7 by screws 69 is a plate 71 having an opening 73 therein. A pin 75 extends through the opening 73 and is threaded into the upper end of the bracket 63. A coil spring 77 around the pin 75 engages the lower face of the plate 71 and the upper end of the bracket 63 and tends to force the bracket downwardly to bring the feed wheel 59 into engagement with the work. A lever 79 is pivotally connected to the upper end of the pin 75 and has a cam end 81 adapted to engage the plate 71. When the lever 79 is in the horizontal position shown in Figs. 1 and 2, it is out of engagement with the plate 71. The spring 77 is then free to force the bracket 63 downwardly to thereby bring the feed wheel into engagement with the work 37 or 37a, as the case may be, and press the work against the supporting wheel 55. However, when the lever 79 is raised to its vertical position, as shown in Fig. 3, its cam end 81 engages the plate 71 to force the pin 75 upwardly against the action of the spring 77. This raises the bracket 63 and thus separates the feed wheel from the work (or from the supporting wheel 55). Thus, sufficient clearance is provided to insert the work between the wheels 55 and 59 endwise from right (as viewed in Figs. 1 and 3) in the case of flat sheets 37, or endwise from the front in the case of the pipes or other similarly curved members 37a. After the work has been suitably mounted in place, the lever 79 is lowered to its horizontal position to bring the feed wheel into engagement therewith. The cam end 81 of the lever 79 is so shaped and dimensioned and the slot 67 is of such length that substantial clearance is provided between the wheels 55 and 59 when the latter is raised. Thus, work of different thicknesses can be accommodated readily.

For actuating the feed wheel 59, a lever 83 is pivotally mounted on the stud 61 behind the feed wheel. Pivotally mounted on the ends of the lever 83 by means of screws 84 are a pair of diametrically opposed pawls 85 which are positioned to engage the serrated periphery of the feed wheel 59. Leaf springs 87 secured to the lever 83 engage the pawls 85 to hold them against the feed wheel. The lever 83 is formed with a slot 89 in which the forward end of an actuating pin 91 is received loosely. The pin 91 is carried by a collar 93 which is secured to the ram 25 by a set screw 95. As the ram moves up and down, the pin 91 rocks the lever 83. The teeth in the pawls 85 and the serrations in the periphery of the feed wheel 59 are so shaped that, as the ram moves

downwardly, the pawls merely slip along the feed wheel periphery, but when the ram moves upwardly, the pawls engage the feed wheel to rotate it a preset distance determined in accordance with the desired spacing between adjacent notches 39. This, of course, determines the width of the tabs 40. To vary the degree of rotation of the feed wheel and thus the width of the tabs, the set screw 95 is loosened and the collar turned slightly one way or the other. This changes the point of engagement of the pin 91 with the lever 83 in the slot 89 and, therefore, the extent to which the lever 83 will be rocked. In turn, this determines the angle through which the feed wheel will be rotated during each cycle and, therefore, the distance through which the work will be advanced. If desired, a leaf spring 97 may be secured to the bracket 63 for engagement with the serrations on the feed wheel periphery to prevent the feed wheel from accidentally rotating in the wrong direction. The slot 89 has a width which is somewhat greater than the diameter of the pin 91 to afford vertical play therebetween. This is to permit the punch 21 to be fully withdrawn from and clear the die and the work before the pin 91 begins to rock the lever 83 so that the work can be advanced freely by the feed wheel.

From the foregoing description, it will be apparent that I have provided an improved notching tool which is simple in construction and easy to operate. Although I have illustrated and described but one embodiment thereof, it will undoubtedly be apparent to those skilled in the art that many variations thereof are possible within the scope of my invention. I therefore desire that the foregoing shall be taken merely as illustrative and not as limiting.

I claim as my invention:

1. Punching apparatus comprising a support including a member adapted to receive a die, a ram carried by said support and movable thereon toward and away from said member, said ram being adapted to receive a punch for cooperation with said die upon movement of said ram toward said member, means for imparting reciprocatory motion to said ram, means including a feed wheel on said support having a work engaging periphery for feeding work over said member, a lever associated with said feed wheel, means carried by said lever and engaging said feed wheel periphery for rotating said feed wheel upon rocking of said lever in a predetermined direction, and lever rocking means carried by said ram, said lever rocking means including a member extending outwardly of said ram in a direction angularly related to the direction of movement of said ram, said last named member extending into engagement with said lever to rock said lever in said predetermined direction upon movement of said ram away from said first named member to thereby effect rotation of said feed wheel.

2. Punching apparatus according to claim 1 characterized in that said lever rocking means is adjustable on said ram in relation to said lever whereby to vary the point of engagement of said last named member with said lever.

3. Punching apparatus comprising a support including a member adapted to receive a die, a ram carried by said support and movable thereon toward and away from said member, said ram being adapted to receive a punch for cooperation with said die upon movement of said ram toward said member, means for imparting reciprocatory motion to said ram, means including a feed wheel on said support having a work engaging periphery for feeding work over said member, a lever associated with said feed wheel, means carried by said lever and engaging said feed wheel periphery for rotating said feed wheel upon rocking of said lever in a predetermined direction, a collar mounted on said ram and movable with said ram, and a pin carried by and extending radially from said collar, said pin extending into engagement with said lever to rock said lever in said predetermined direction upon

movement of said ram away from said member to thereupon effect rotation of said feed wheel.

4. Punching apparatus according to claim 3 characterized in that said collar is circumferentially adjustably mounted on said ram for varying the point of engagement of said pin with said lever to thereby determine the degree of rocking of said lever and thus the degree of rotation of said feed wheel.

5. Punching apparatus comprising a stand having a base, an upright above said base, and a block extending from said upright over and in spaced relation to said base, a die mounted on said base, a ram carried by said block for reciprocatory movement relative to said die, means for reciprocating said ram, a punch carried by said ram for cooperation with said die, a work supporting wheel mounted on said base, a bracket slidably carried by said block for limited movement thereon toward and away from said work supporting wheel, a feed wheel on said bracket in alignment with said supporting wheel having a serrated periphery adapted to engage work on said supporting wheel when said bracket is in a position nearest to said base, spring means associated with said bracket influencing said bracket to said position, means associated with said bracket for moving said bracket against the influence of said spring means to a second position relatively remote from said base to thereby disengage said feed wheel from the work, a lever carried by said bracket, pawl means carried by said lever for engagement with said feed wheel periphery to rotate said feed wheel when said lever is rocked in a predetermined direction, and actuating

5
10
15
20
25
30

means for said lever carried by said ram and engaging said lever, said actuating means being operable to rock said lever in said predetermined direction when said ram moves away from said die.

6. Punching apparatus according to claim 5 characterized in that said lever has a slot therein, and characterized further in that said lever actuating means comprises a collar on said ram and a pin extending from said collar into said slot.

7. Punching apparatus according to claim 6 characterized in that said pin and said slot have such dimensions that said pin has play within said slot in the directions of motion of said ram whereby, when said ram moves away from said die, said punch will be fully withdrawn from said die and the work before said pin will begin to rock said lever in said predetermined direction.

8. Punching apparatus according to claim 6 characterized in that said collar is adjustable circumferentially on said ram for varying the point of engagement of said pin with said lever to thereby control the degree of rocking of said lever and thus the degree of rotation of said feed wheel by said pawl means.
